Howard and Howard Atty's.

UNITED STATES PATENT OFFICE.

WILLIAM R. YOUNG, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CURRENT-TAP.

1,226,433.

Specification of Letters Patent.

Patented May 15, 1917.

Application filed January 30, 1917. Serial No. 145,431.

To all whom it may concern:

Be it known that I, WILLIAM R. YOUNG, a citizen of the United States of America, and residing at Bridgeport, in the county of 5 Fairfield and State of Connecticut, have invented a certain new and useful Improvement in Current-Taps, of which the following is a specification.

My invention relates to current taps and 10 particularly to a combined tap and receptacle affording connecting means for a plurality of attachment plugs. It not infrequently happens that but a single outlet is available at the point at which it is desired 15 to effect a plurality of connections to current utilizing appliances and it is often the case that the current utilizing devices are fitted with attaching plugs of different constructions or different from the type of receptacle provided at the outlet. The present invention provides a fitting adapted to be 20 tapped into the outlet and affording a plurality of receptacles each of which is adapted to receive attaching plugs of different 25 types. The object of my invention is to provide a rugged device of this type which may be cheaply manufactured without sacrificing either strength or serviceability.

As shown in the accompanying drawing, 30 Figure 1 is a front elevation of a tap embodying my invention in one form;

Figs. 2 and 3 are opposite end elevations thereof;

Fig. 4 is an interior plan of the fitting, 35 the body portions of the latter being detached and separated;

Fig. 5 is a section on the line 5—5, Fig. 1; and

Figs. 6 and 7 are perspectives of the 40 respective terminal plates.

As here shown the present fitting comprises a cylindrical body of insulating material formed of two blocks 10 and 11 each provided with a lateral extension 12, 13, 45 which combine to afford a cylindrical boss located at right angles to the axis of the body of the fitting. Passing out through this boss and seated in channels 14 and 15 in the respective body parts 10 and 11, are 50 spaced jacks 16 and 17 for tapping current from a suitable outlet. The jack 16 is integral with the angled terminal plate 18 extending into the area of the cylindrical body 55 of the fitting. The jack 17 in like manner is integral with the terminal plate 19 which

is angled into another portion of the area of the cylindrical body of the fitting. Appropriate recesses 20 and 21 are formed in the meeting faces of the body portions 10 and 11 to receive the terminal plates 18 and 19 and hold the same against angular displacement. Securing screws 22 and 23 take into tapped members carried by the respective body portions and hold the terminal plates securely in position. The screw-receiving members may take the form of flanged thimbles 24 and 25. The body of the fitting is preferably molded from insulating material of such character that the thimbles may be positioned therein during 70 the molding operation, in which case the flanges serve as anchors for holding the thimbles in fixed position.

The cylindrical body portions are pierced in register at 26, 27, 28, 29, to receive the 75 two pairs of receptacle terminals 260, 2600; 270, 2700; and 280, 2800; 290, 2900, carried by the respective terminal plates 18 and 19 and projecting on opposite sides of the latter into the passages in the cylindrical body 80 of the device. These passages or guideways are so arranged as to receive the substantially parallel or tandem jacks of a co-operating attachment plug. It is thus obvious that a plug having parallel jacks may be inserted 85 at either end of the body of the fitting into engagement with the parallel terminals 260 and 280, or 2600 and 2800, while at the opposite end of the fitting a plug may be utilized having tandem jacks which enter the channels 27 and 29 and engage the terminals 270 and 290 or 2700 and 2900 therein. Or two similar attachment plugs with their blades either in parallel or in tandem may be utilized for connection to the fitting.

The two part insulating body portions may be provided on their meeting faces with positioning studs 30 and 31 which take into corresponding recesses 300 and 310 in the associated block. Screws 32 and 33 pass 95 longitudinally through the opposite body sections 10 and 11, and take into tapped sockets to clamp the parts rigidly together.

The terminals 16 and 17 may be arranged in other ways than in parallel. Similarly 105 it is not essential that the plates 18 and 19 be integral with the blades 16 and 17 so long as they are electrically connected.

Various modifications of arrangement of the parts and details of construction will 110

readily occur to those skilled in the art which do not depart from what I claim as my invention.

I claim:

- 5 1. A tap device comprising coöperating body portions of insulating material pierced in register, conducting plates arranged between the juxtaposed faces of said body portions and having terminals projecting from both sides of said plates into said piercings, in combination with tap terminals electrically connected to said plates and extending at right angles to the axis of the body for connection to a current outlet.
- 10 2. A tap device comprising coöperating body portions of insulating material pierced in register, conducting plates arranged between the juxtaposed faces of said body portions and having terminals projecting from opposite sides of said plates into said piercings, said terminals being arranged to receive jacks of coöperating plugs of different types.
- 15 3. A tap device comprising coöperating body portions of insulating material pierced in register, conducting plates arranged between the juxtaposed faces of said body por-

tions and having terminals projecting from opposite sides of said plates into said piercings, said terminals being arranged to receive either parallel or tandem jacks of a coöperating plug.

4. A tap device comprising a pair of insulating blocks shaped to form a body having a boss projecting at right angles to the axis thereof, jacks passing through said boss, terminal plates integral with said jacks and lying between the juxtaposed faces of said body parts, each of said plates carrying on its opposite faces terminal means for co-operating with jacks of different type, said body portions being pierced to afford guideways in which said terminals lie.

5. In a tap device, a jack, an integral terminal plate and jack-receiving terminals attached to the opposite faces of said plate.

In testimony whereof, I have signed my name to this specification, in the presence of two subscribing witnesses.

WILLIAM R. YOUNG.
